DESIGN FOR A WATCHCASE

Paul A. Schwankhaus, Dayton, Ky., assignor to
The Wadsworth Watch Case Company, Dayton,
Ky., a corporation of Kentucky

Application June 24, 1938, Serial No. 78,014

Term of patent 7 years

To all whom it may concern:

Be it known that I, Paul A. Schwankhaus, a citizen of the United States and a resident of Dayton, in the county of Campbell and State of Kentucky, have invented a new, original, and ornamental Design for a Watchcase, of which the following is a specification, reference being had to the accompanying drawing, forming part thereof.

In the drawing:—

Figure 1 is a face view of the watchcase showing my new design.

Figure 2 is a side view thereof showing the parts in that relationship which they assume when the case is worn on the flat of the wrist.

Figure 3 is a side view showing the parts in that relationship which they assume when the case is worn on the edge of the wrist.

Figure 4 is a back view of the watchcase.

I claim:—

The ornamental design for a watchcase, substantially as shown and described.

PAUL A. SCHWANKHAUS.
